UNITED STATES PATENT OFFICE

CHARLES W. KIRSCH, OF STURGIS, MICHIGAN, ASSIGNOR, BY MESNE ASSIGNMENTS, TO
KIRSCH COMPANY, OF STURGIS, MICHIGAN, A CORPORATION OF MICHIGAN

DRAPERY-SUSPENSION FIXTURE

Application filed January 31, 1927. Serial No. 164,693.

This invention relates to improvements in the drapery suspension art and more particularly to that type of devices designated curtain poles as distinguished from curtain rods and has for its several objects to provide a curtain pole and associated drapery supporting and operating means arranged and constructed to provide smooth and easy traverse of the suspension means on the supporting pole; provide carriers included in the suspension means which are so engaged with the pole as to be held against removal and rotation relatively to the latter and are so engaged with rings or the like to which the draperies are attached as to maintain said rings or the like disposed in a given position relatively to the pole; wherein the carriers for said rings or the like are so coupled as to cause all of the same to be suitably spaced from each other when the draperies are disposed with their meeting edges in contact with each other or overlapped and to relieve the draperies of all strains incident to the operation of spacing them from each other and bringing them together; and to provide means for so associating the draperies with the suspension means as to permit the former to readily adjust themselves to the relative positions of the latter.

The invention in its preferred embodiment is suitably illustrated in the accompanying drawings wherein:

Fig. 1 is a plan view of a curtain pole equipped with suspension means and operating devices therefor constructed in accordance with the invention, the suspension means being shown partly in section.

Fig. 2 is a fragmentary detail plan view on an enlarged scale of the curtain pole of Fig. 1 to illustrate a detail of construction.

Fig. 3 is a transverse section on the line 3—3 of Fig. 2.

Fig. 4 is a perspective view of one of the master carriers of the pole.

Fig. 5 is a perspective view of one of the intermediate carriers of the pole.

Fig. 6 is a view similar to Fig. 1 showing a modified form of construction.

Fig. 7 is a fragmentary front elevation of

a pole and suspension device constructed in accordance with the invention.

Fig. 8 is a fragmentary bottom plan view of the structure of Fig. 7 showing a suspended drapery in section.

Fig. 9 is a fragmentary perspective view of a modified form of carrier and drapery supporting device employed.

The curtain pole 1, usually made of wood and of various cross-sectional shapes, is here illustrated as being cylindrical. This pole is provided with a longitudinal groove 2, here shown as having a flat bottom and perpendicular side walls, in which there is suitably mounted a conventional C-shaped curtain rod 3 having its longitudinally slotted wall exposed, the flanges 4 bordering the slot in said rod being utilized to support carriers 5 and 6 for rings 7 or equivalent devices from which draperies are suspended. Each slide 5 or 6 comprises a flat plate having parallel end flanges 8 provided with side recesses 9 in which the said flanges 4 engage. Each slide is also equipped with means for attaching a cord thereto, the slides 5 being what are known as "master slides" and being adapted to be attached to the ends of the draw-cord 10. Only two of the slides 5, are used and each thereof is provided between its ends with a slot 11 bordered at one side by a hook-like projection 12, a loop of the cord 10 being passed through said slot and over the said projection to firmly but detachably secure said cord to the slide with resort to knotting.

Each slide or carrier 5 and 6 is provided with what I term a "saddle" in which the ring 7 is engaged to hold the latter against movement longitudinally of the carrier and also maintain it perpendicularly disposed relatively to the pole 1 to thus maintain all the said rings 7 parallel with each other. The saddles, in the instance illustrated, consist of pairs of projections 14 and 15 extending upwardly from the side edges of the plates and spaced from each other a distance slightly less than the thickness of the ring 7, the opposed edges of the projections 14 and 15 being inclined to diverge from the sur-

face of the plate to the outer ends of said projections.

It will be obvious, of course, that the details of construction of the slide may be changed and varied to adapt the same to other forms of rods and that rods of other forms may be substituted for the rod 3 herein illustrated, the invention residing in a combination of rod and carriers capable of functioning substantially as the rod and carriers herein illustrated function. It will also be obvious that other drapery suspension devices than the specific type herein illustrated may be associated with the carriers without departing from the invention as defined in the appended claims.

In every instance wherein it is desired to employ the draw-cord 10 to manipulate the draperies suspended from the members 7, a 20 pair of master slides 5 disposed for supporting the members 7 carrying the meeting edge portions, is employed, together with such number of the slides or carriers 6 as may be desired to support the members 7 carrying 25 the outer edge and intermediate portions of the draperies, but if the draw-cord 10 is omitted all slides used will be of the type of Fig. 5.

It will be obvious that where the draw-cord 10 is employed, the necessary sheaves therefor must also be provided, the particular manner of associating the sheaves with the rod 3 being selective according to other details of construction such, for example, as 35 are illustrated and described in Letters Patent No. 1,494,429 dated May 20, 1924; Nos. 1,606,580, 1,606,581, and 1,606,582 dated Nov. 9, 1926, modified as far as necessary to adapt them to this particular purpose.

40 The above described structure presents a very easily and smoothly operable fixture wherein no movable part contacts with the pole surface to mar the same or hinder its free travel.

45 In place of using the rings 7, the substantially semi-circular metallic suspension members 20 (Figs. 6, 7 and 8), which may be shaped between their extremities as desired to simulate wooden rings of the type shown 50 in Figs. 1 and 2 or to present an ornamental appearance, may be employed some of said members 20 being shown in Fig. 6 as flat semi-cylindrical pieces of sheet metal riveted to the carriers. The members 20 are provided at their ends with flat flanges 21 and 22, the upper flanges 21 being pivotally secured to projections 23 on slides 25, substituted for slides 5 or 6 and of generally similar construction. The lower flanges 22 of 60 said members 20 are provided with perforations to pivotally engage the drapery attaching means such as the members 50.

The rod 3 is preferably of less length than the pole 1 and its groove 2 to provide spaces 65 beyond the ends of the rod to receive the

sheaves 26, 27, and 28 and carriers 29 and 30 therefor, over which the draw-cord 10 is trained in the customary manner, the pole being provided with an opening 31 through which a loop of the cord 10 is passed to depend for manual operation of the slides or carriers 5. 70

In the operation of the carriers or slides 5 and 6 or their equivalents wherein the suspension members are capable of swinging on a horizontal axis, it not infrequently happens that, because of the fact that all slides except the master-slides, are moved to spaced position by tension on the upper edge of the drape, that resistance to movement of the slides causes the suspension members carried thereby to swing on said horizontal axes of their pivotal connections with the slides and strike the lower portion of the pole and not only mar the same but bind thereon. To overcome this and also obviate the necessity of plaiting the drapes and secure the several advantages heretofore pointed out preceding the brief descriptions of figures in the drawings, I provide the slides 5 and 6 with means for easily attaching a spacing-cord 45 thereto. Thus the master-slide 5 is provided in the end flange 8 opposing the next succeeding slide 6, with a perforation 46 through which and the opening 11 one end of said spacing-cord 45 is passed and tied. The several slides 6 are provided with central openings 47 from one wall of which a pair of tongues 48 are struck up to extend angularly to the top face of said slide, the cord 45 being adapted to be wedged between said tongues 48 and the end walls of the opening 47 to prevent relative longitudinal movement between the cord and the slide. The projections 14 and 15 back of the tongues 48 are provided in their opposed edges adjacent their junctures with the plate or body of the slide, with recesses 49 through which the cord 45 also passes and in which it is wedged. The recesses 49 are provided in those projections 14 and 15 which oppose the window casing so that the portions of the cord 45 spanning the spaces between consecutive slides will be maintained invisible and, when slack, will project the resulting loops toward said casing. 95

The cord thus connects the master-slide with the next succeeding slide and the latter with the next succeeding and so on. As the meeting of the master-slides limits the movement of the entire chain associated with each thereof, the cord 45 terminates at the last slide of each chain or series of slides and serves to space all of the latter equi-distantly, or as desired, from each other in the order of their succession with respect to the master-slide as the latter moves from an end portion toward the middle of the pole. 100

This spacing of the slides by means of the cord 45 permits the omission of plaits along the upper edge portion of the drapes so as to 105 110 115 120 125 130

provide loose fullness throughout the length of said drapes between successive points of suspension and to further this arrangement and prevent sagging of the full portions between points of suspension, the suspension members mounted on the slides 6 may be provided with bars 50 pivotally secured midway between their ends to the lowermost portions of the rings 7 or members 20 for rotation about vertical axis and provided at their extremities with hooks 51 to engage in cord loops 52 stitched to the drapes to thus provide spaced points of support of less span than the distance between centers of successive slides to thus prevent sagging, as above suggested, and permit the slack portions of the drapes between successive slides to arrange themselves in convolutions as shown in Fig. 8. If, however, plaiting is resorted to, it will be obvious that the spacing-cord 45 will alone bear all of the tension stress necessary to move the slides 6 as the master-slide is moved toward the middle of the curtain rod or pole so that the rings 7 or members 20 will not be caused to swing on the horizontal pivotal axes of connection with the slides.

The type of slide 20 shown in Figs. 7, 8, and 9 may be provided with means for readily attaching the cord 45 thereto, this consisting in providing the plate or body 25 of said slide with end flanges 53 provided with edge recesses 54 and in providing angular wedge slots or recesses 55 in the two end portions of said plate 25, the mouths of said recesses communicating with the slot out of which the flange 23 is struck up. A loop of the cord 45 is engaged and wedged into the said recesses 55 and its side portions engaged in the recesses 54.

It will be understood, of course, that the several means for engaging loops of the cord 45 with the slides 5 and 6 shown are merely exemplary of suitable and convenient devices adapted to the purpose, the invention residing, as I am informed, in the use of slide or suspension devices spacing means other than the drape or drapes secured to and supported by said devices.

Practically all separable draperies are operated by means of draw-cords and this feature of the present invention relating to spacing of slides or carriers from each other independently of the draperies, is more particularly applicable to draw-cord operated devices. It will also be observed that the spacing cord or its equivalent in combination with the slides forms an articulate drapery carrying structure.

In the case of the rings 7, it will be appreciated that the sharp edges of the projections 15 forming the saddle supports for said rings will, by reason of biting of the sharp edges into the rings, prevent the latter from rotating about the pole axis so that said saddles coact with the spacing-cords 45 to main-

tain the rings always in the same position with respect to the pole in which they are normally held by the weight of the draperies.

I claim as my invention:

1. In a curtain or drapery fixture including a rod, drapery carriers slidably mounted on said rod, drapery suspension devices pivotally associated with said carriers for swinging on horizontal axes extending transversely of the rod, and drapery attaching bars pivotally mounted upon the lowermost portions of said suspension devices for rotation about vertical axes.

2. In a curtain or drapery fixture including a rod, drapery carriers slidably mounted on said rod, drapery suspension devices pivotally associated with said carriers for swinging on horizontal axes extending transversely of the rod, and drapery attaching bars pivotally mounted upon the lowermost portions of said suspension devices for rotation about vertical axes, and a spacing cord connecting all of said carriers.

3. In a curtain or drapery fixture including a rod, drapery carriers slidably mounted on said rod, drapery suspension devices pivotally associated with said carriers for swinging on horizontal axes extending transversely of the rod, and drapery attaching bars pivotally mounted upon the lowermost portions of said suspension devices for rotation about vertical axes, a spacing cord common to all of said carriers, and a draw-cord connected with one of said carriers.

4. A curtain fixture comprising a curtain pole having a longitudinal slot therein bordered by opposed metallic flanges constituting a pair of rails, drapery carriers mounted for travel on said rails and equipped with projections engaging underneath the same, pairs of upstanding projections on said carriers, and drapery suspension devices detachably mounted on said carriers and engaged by said projections to hold the same against longitudinal movement relatively to said carriers, said projections presenting sharp edges engaging said devices to prevent movement thereof laterally of said carriers.

5. A curtain pole provided with a longitudinal groove, a conventional hollow, longitudinally slotted curtain rod mounted in said groove and having its slotted wall disposed in the mouth of said groove, sheaves and carriers therefor mounted in said groove between the ends of said rod and the ends of said pole, two sets of carriers, each including a master carrier, engaged with the slotted wall of said rod and slidably on the latter, a draw-cord engaged with said sheaves and said master carriers, and drapery suspension devices mounted on said carriers.

6. A curtain pole provided with a longitudinal groove, a conventional hollow, longitudinally slotted curtain rod mounted in said groove and having its slotted wall dis-

posed in the mouth of said groove, sheaves and carriers therefor mounted in said groove between the ends of said rod and the ends of said pole, two sets of carriers, each including a master carrier, engaged with the 5 slotted wall of said rod and slideable on the latter, a draw-cord engaged with said sheaves and said master carriers, and spacing cords engaged with said master carriers and the remaining carriers of each of the respective 10 sets.

7. A curtain fixture including a pole having a longitudinal groove, flanges overhanging said groove, traveling carriers comprising plates having end flanges projecting into 15 said groove and provided with side recesses in which said flanges engage, upwardly extending pairs of side projections on said plate bordering spaces, drapery suspension rings engaged in said spaces, and means on 20 said plate for detachably engaging a cord therewith.
